PETER AITCHISON, OF NEW ROCHELLE, NEW YORK, ASSIGNOR TO AMERICAN BANK NOTE COMPANY, OF NEW YORK, N. Y., A CORPORATION OF NEW YORK.

PAPER-WETTING MACHINE.

Application filed April 18, 1924. Serial No. 707,433.

My invention relates to a paper wetting machine, and more particularly to a machine of this type in which the paper or sheet will be rapidly and thoroughly dampened so as to be properly conditioned for use in the making of impressions thereon, by a printing machine.

Heretofore, various types of wetting machines have been used for conditioning paper, a highly developed type of this machine including therein endless strips of absorbent fabric or blankets, adapted to receive between them sheets of paper, the blankets being subject to the action of presser rolls while the paper was between parallel reaches of co-operating blankets. The blankets in some instances were passed through a bath of the dampening liquid, with the paper, while in other instances, according to the quality of the paper used, the blankets themselves, after being properly saturated with such liquid, had the paper fed between them and were merely passed between the presser rollers.

In such machines, not only is there presented the difficulty of keeping the co-operating blankets straight, but the machine is required to be of considerable length in order to secure an effective wetting or dampening of the paper, pressure being applied through the blankets to the paper only for a short interval, or intervals during the movement of the blankets.

Such machines have been found to give highly satisfactory service in uniformly dampening each sheet of paper, but at times, and with different grades of paper, there has been a tendency of such machines to have irregular dampening or wetting action upon different sheets, and there has also been some difficulty experienced in maintaining a uniform degree of saturation in all parts of both blankets, which contributed in large measure, to variances in the condition of different sheets. This is particularly true when the machine is run at high speeds.

The blankets used in such machines are also of a considerable length, and the pressure conditions between the parallel adjacent reaches of co-operating blankets through stretch of one blanket or the other, results not only in a lack of uniformity in the pressure exerted upon the sheets of pa-

per by the blankets, but a lack of such tautness in the blankets as is required to secure an effective pressure upon the sheets at all times while they are contained between the parallel reaches of such blankets.

With the above conditions in mind I have devised a paper wetting machine in which the sheets of paper to be dampened or wetted are delivered between two moving absorbent bodies, one of which is a blanket carried by a rigid rotatable backing, and the other of which is endless and passes about suitable guides during its movement, so as to be brought and maintained with sufficient pressure upon sheets of paper positioned between these two blankets, to cause the dampening liquid to be quickly forced within the fibres of the paper. While the paper is positioned between the two absorbent bodies, they have movement together through a bath of liquid, the width of these bodies, however, being such that the dampening medium applied to the paper will be merely that resulting from the expression of the liquid from said absorbent bodies, as a result of the pressure developed by the endless blanket, due to the presence of a rigid backing for the other blanket, and the guiding arrangement for the endless blanket. This will ensure the maintenance of a maximum amount of moisture in the absorbent bodies without likelihood of injury to, the surface dressing or sizing of the paper.

The machine of my invention is so constructed that the rigid member carrying and forming a backing for one of said blankets, will positively grip each sheet of paper delivered thereto, so as to ensure its proper position with relation to both blankets. The machine includes therein a collecting mechanism receiving the dampened sheets from said rotatable member, and collecting them in a pile or stack. The sheets are permitted to remain piled or stacked until used, the stacking of such sheets having the effect of aging the sheets so as to have them properly conditioned, although the methods of dampening or wetting by this machine are such that the sheets, if desired, may be moved directly from the wetting machine to the printing press, and still secure a good clean impression without further aging.

In a machine embodying my invention

one of the co-operating absorbent blankets is carried by a rigid cylinder forming a backing therefor, while the other absorbent body is in the form of an endless blanket, the major portion of which is always submerged in liquid in a tank, so that said absorbent blanket will always contain substantially the maximum volume of liquid in all parts thereof. All liquid expressed from any part of either blanket is replaced by liquid absorbed by that portion of the blanket after a sheet upon which it acts has passed from engaging relation therewith, and before another sheet is fed in relation to that portion of the blanket.

Preferably after a sheet has passed from between the two moving absorbent bodies, but is still engaged with one of these bodies, it is subjected to the action of a squeeze roller which will serve to effectively force superficial liquid within the fibres of the paper, or remove it from the paper while, at the same time, forcing each sheet of paper firmly against the blanket between it and the rigid backing therefor.

While the form of collecting mechanism used is immaterial to my invention, better results are to be had if it be so constructed as to carry the sheets for a short distance after leaving the liquid applying mechanism, so as to give each sheet an opportunity to completely absorb the liquid applied thereto, before the sheets are piled or stacked and avoid the presence of free surface liquid which might result in one sheet absorbing the moisture from another sheet, resulting in irregularity of the wetting action as to different portions of different sheets. It is desirable, in wetting paper, to not only have all sheets wet or dampened in substantially the same degree, but to have different portions of the sheet uniformly conditioned.

The invention consists primarily in a paper wetting machine embodying therein a tank for the wetting liquid, a cylinder rotatably mounted within said tank, a yieldable blanket carried by said cylinder, an endless absorbent blanket adapted to co-operate with the blanket upon said cylinder during a portion of each revolution of said cylinder, and guides for the operative reach of said endless blanket in pressure relation to said cylinder and for the inoperative reach of said endless blanket positioned below the level of the wetting liquid within said tank and away from said cylinder whereby the operative reach thereof is pressed tightly against the blanket upon said cylinder, and the inoperative reach thereof is passed through the liquid in said tank, so that a sheet delivered between said blankets will be subjected to continuing pressure for a part of a revolution of said cylinder, and the moisture expressed from a blanket as a result of the pressure exerted

by one of them upon the other, will be restored before the same portion of the blanket is brought into engaging relation with another sheet; and in such other novel features of construction and combination of parts, as are hereinafter set forth and described and more particularly pointed out in the claims hereto appended.

Referring to the drawings,

Fig. 1 is a vertical section through a paper wetting machine embodying my invention, the showing of the feeding mechanism and the collecting mechanism being largely conventional;

Fig. 2 is an enlarged view showing the relation of the blanket cylinder, the endless blanket and its guides, the gripper mechanisms upon said cylinder, and the squeeze roller, the feeding and the collecting mechanisms being omitted; and

Fig. 3 is a plan view of Fig. 2.

Like numerals refer to like parts throughout the several views.

In the embodiment of my invention shown in the drawings, I employ a tank 10 which may be made of any suitable material such as wood, so lined as to hold liquid. Rotatably mounted within this tank is a cylinder 11 having about its perimeter a suitable yieldable blanket, preferably including two absorbent blankets 12 and 13, one superimposed upon the other, so as to give the desired thickness to the absorbent facing for said cylinder.

The blankets 12 and 13 are ordinary felt blanks commonly used in the printing art, although no particular material is required for such blankets so long as it is of a nature to be sufficiently flexible and thick to permit the transfer of moisture therefrom, during the wetting or dampening operation, to sheets of paper.

Associated with the cylinder 11 is a feed shelf 14 and a feeding mechanism 15 adapted to receive sheets from said shelf and transfer them to the cylinder 11. This feeding mechanism may be of any desired type, the speed of operation of the machine being such as to readily adapt it for use with automatic feeders.

The cylinder 11 has mounted thereon one or more gripper mechanisms 16, three such mechanisms being used in the form of the invention shown, since the circumference of said cylinder 11 is sufficiently great to permit three sheets to be simultaneously acted upon by said cylinder while the machine is in operation.

The surface of the cylinder 11 is recessed to receive the gripper mechanisms 16, thus interrupting the continuity of the facing formed by the blankets 12 and 13, continuity of this surface not being required since the arc between the gripper mechanisms is sufficiently great to accommodate the largest

sheet which is to be dampened upon the machine.

The cylinder 11 affords a rigid backing for the blankets 12 and 13 in order to permit the effective expression of moisture either from said blankets 12 and 13 themselves, or from a blanket 17 co-operating therewith, and the forcing of this moisture within the fibres of the paper as a result of the application of pressure thereto from said endless blanket 17 co-operating with the cylinder 11 and having a speed of lineal traverse substantially coinciding with the angular speed of the cylinder 11.

15 The blanket 17 passes about suitable guides 18, 19, 20 and 21 so positioned as to tension said blanket 17 in a manner to develop a continuing pressure of one reach thereof toward the cylinder 11 and upon the blankets 20 12 and 13 carried by said cylinder, and the paper sheet between the outer of said blankets 12 and the endless blanket 17. The guides 18, 19, 20 and 21 are, in the form 25 of the invention shown, ordinary rollers positioned within or above the tank 10 in order to facilitate the free movement of the blanket 17. The rollers 18 and 19 define the point of operative engagement of the blanket 17 with, and the point of disengagement of 30 said blanket from the blanket 12, these points respectively being adjacent the feeding mechanism 15, and adjacent a collecting mechanism 22 to be more fully referred to hereinafter. The rollers 20 and 21 are mere 35 guide rollers for directing the inoperative reach of said blanket 17 through the liquid in the tank 10, in a position where the blanket 17 will be properly exposed to said liquid, so that it will, by absorption, take 40 up enough liquid to replace that absorbed by the paper and expressed from the blanket during the interval of pressure engaging 45 relation of said blanket with the paper and the blankets 12 and 13. At the same time the rollers 20 and 21 will assist in developing the desired tautness in the blanket 17 to ensure the requisite application of pressure by 50 said blanket throughout that portion of the length thereof which is in engaging relation with the blankets upon the cylinder 11.

The roller 18 in addition to serving as a guiding and tensioning roller for the blanket 17, also serves as a driving roller for this blanket. Said roller is mounted in adjustable bearing blocks 22 carried between adjusting screws 23 and 24 to permit movement of this roller for the purpose of developing the desired tautness in the blanket 17.

55 The cylinder 11 is driven by means of a large gear 25 carried by an arbor upon said cylinder, said large gear 25 meshing with a small gear 26 driven from any desired source of power as the motor 27. The tensioning, 60 guiding and driving roller 18 is driven from

the gear 25 by the gear train 28, 29 and 30, the first of which gears also supplies power for actuating the feeding mechanism 15 through the gears 31 and 32.

The various rollers 18, 19, 20 and 21 may 70 be made of any desired material, wood preferably being used for these rollers as well as for the cylinder 11 in order to avoid likelihood of discoloration of the wetting mechanism, or the blankets as the result of 75 the action of the wetting liquid thereupon.

Associated with the cylinder 11 is a squeeze roller 33 driven from the gear 25 by the gear train 34, 35 and 36. The roller 33 is in a position to engage the outer blanket 12 upon 80 the cylinder 11 after the blanket 17 has passed from its engaging relation with said blanket to about the roller 19, and apply pressure to each sheet of paper after it has been relieved from the surface pressure between the blankets 12 and 17. This pressure, although limited by substantially lineal contact between two cylindrical bodies, serves to either force surface liquid carried by the 85 paper sheet within the fibres of the paper, or remove this liquid from the paper in the event that the paper has become fully saturated with the liquid.

The point of separation of the blankets 12 and 17, adjacent the guide roller 19, is above 90 the normal level of the liquid in the tank 10, so that the paper itself is not subjected directly to the action of the liquid within the tank.

The roller 33 is preferably made of non-absorbent yet yieldable material, its purpose being not to apply liquid to the paper sheet, but to assist in the quick distribution of the liquid throughout the sheet, and give 100 a final pressure upon a sheet while it is engaged solely with the blanket 12.

Beyond the squeeze roller 33, in the direction of the rotation of the cylinder 11, is a collecting mechanism consisting of endless chains 37 passing about suitable spaced pairs of sprocket wheels 38 and 39. These chains carry gripper bars 40 adapted to receive sheets of paper from the grippers 16 upon the cylinder 11 and convey them to a collecting table 41. The gripper bars 40 are 110 spaced apart upon the chains 37 a distance coinciding with the distance in arc between the grippers 16 upon the cylinder. The shafts of the wheels 38 and 39 carry wheels 42 about which supporting wires or tapes 115 43, pass.

The sprocket wheels 38 are driven from the gear 34 by an intermediate gear 44 meshing with a gear 45 carried by the shaft of said 120 sprocket wheels 38.

The driving mechanisms of the machine are such that the peripheral speed of the blanket 12 will be the same as the speed of the blanket 17, and the same as the peripheral speed of the squeeze roller 33. At the 130

same time the rate of lineal travel of the chains 37 corresponds with the peripheral speed of the cylinder 11.

The particular form of gripper mechanism used in connection with the cylinder 11 and the chains 37 is immaterial to the invention, grippers of various types being old and well known in the printing art. Hence a detailed description of these mechanisms, as well as of the opening and closing means therefor, is unnecessary. The details of the feeding mechanism and the collecting mechanism, are also immaterial to the present invention, except that the spaced relation of the pairs of sprocket wheels 38 and 39 is preferably such as to permit the exposure of the sheet to the surrounding atmosphere for a sufficient interval to permit a more or less uniform diffusion of the wetting liquid throughout the entire sheet, an action known in this art as aging, and which results in the elimination of stiffness or hardness in every portion of the paper.

The roller 33 is mounted in adjustable bearing blocks 46 acted upon by adjusting screws 47 and 48 so as to permit the regulation of the pressure applied by said roller upon a sheet of paper carried by the cylinder 11.

In the drawings, I have indicated the sheets of paper at 49, it being understood that the machine is designed for wetting or dampening paper sheets, and not a continuous strip or web of paper.

The roller 19 is mounted in a bearing block 50 acted upon by a lead screw 51, by which said bearing block 50 may be raised to take up slack in the blanket 17 due to elongation of said blanket from stretch, or as a result of the adjustment of the roller 18 for developing the desired pressure of said roller upon the blanket 17, where it passes into engaging relation with the blanket 12. Hence both of the rollers 18 and 19 may be adjusted in defining the pressure exerted by the roller 18 as well as the pressure of the blanket 17 upon the blanket 12 as to the reach thereof between said rollers.

The operation of the herein described machine is substantially as follows:

The sheets of paper 49 are placed upon the feed shelf 14 and fed one sheet at a time by the feeding mechanism 15. As each set of grippers 16 reaches the proper relation to the grippers of the feeding mechanism, a sheet of paper will be delivered thereto, so as to be carried downwardly by the cylinder 11.

In the meanwhile, the blankets 12 and 13 have been thoroughly saturated as a result of their immersion in the liquid tank 10, as will also the blanket 17. The continued rotation of the cylinder 11 will bring the sheet of paper between the blanket 12 rearwardly of the grippers engaging said sheet, and the

operative reach of the blanket 17, so that ultimately the entire surface of said sheet of paper 42 will be simultaneously subjected to pressure from the blanket 17 toward the blankets 12 and 13. This pressure will not only serve to transfer the surface moisture from the blankets 12 and 17 to the paper sheet, but will literally force the moisture from these blankets 12 and 17 within the fibres of the paper, the paper not only taking up this surface moisture, but receiving moisture expressed from both blankets 12 and 17.

As each sheet of paper passes between the blankets 12 and 17, it will receive pressure through the blanket 17 directly from the roller 18, thus tending to not only force moisture into the paper at the point of its initial engagement between said blankets, but since a dry sheet will not readily absorb moisture, creating a surplus of free liquid between the sheet and the blanket 17, in excess of the normal supply of surface liquid upon the blanket. This will be spread by the blanket 17 throughout the entire surface of the paper. In this manner a rapid initial wetting of the surface of the paper is secured, so that the continued pressure upon the paper, while it is between the blankets 12 and 17, will result in a rapid absorption by the body of the paper, of moisture expressed from either or both of these blankets.

There being no relative movement of the blankets 12 and 17, the surface finish of the paper will not be disturbed in any way.

While the R. P. M. of the cylinder 11 may be varied to accommodate the machine to different grades of paper, the period during which the paper will be thus subjected to pressure between the blankets 17 and 12 will never exceed more than two or three seconds, this interval having been found sufficient to properly wet the higher grades of paper, bond papers requiring a greater length of time than the softer linen papers. The time interval might be further reduced with still lower grades of paper.

As the blanket 17 passes from its pressure engaging relation with the blanket 12, the sheet of paper will continue upon the cylinder 11, and will pass the squeeze roller 33 having rotary movement in the same direction, with relation to the engaging point of said roller and said cylinder, and at the same speed as the blanket 12. By reason of the cylindrical, non-absorbent surface of the roller 33, there will be only lineal contact or substantially lineal contact between this roller and the sheet of paper, the pressure being merely sufficient to force the paper firmly against its backing blanket 12, so as to secure a more effective wetting of the side of the paper presented toward said blanket. At the same time, the roller 33 will tend to distribute any surface moisture upon the

sheet of paper and remove any such moisture in the event of there being surface moisture in excess of that required to thoroughly wet or dampen the sheet.

5 The squeeze roller 33 engages the paper 49 upon the cylinder 11 above the normal level of the liquid in the tank 10 and is so located that any liquid removed from the paper sheet, will flow back to within the tank 10.

10 After leaving the squeeze roller, each gripper mechanism 16 will be actuated as it reaches the engaging relation with the grippers 40 upon the chains 37, thus permitting the transfer of the sheet from the cylinder

15 11 to the collecting mechanism by which it will be conveyed, while exposed to the atmosphere for an interval of a few seconds, to, and be deposited upon the stack upon, the collecting table 41. This exposure of 20 the sheet is for an interval insufficient to permit any noticeable evaporation of the wetting medium, while permitting the paper to readily take up any surface moisture which may remain thereon, or permit each sheet to 25 thoroughly absorb the moisture which has been applied thereon, so as to take all stiffness or hardness out of the paper, and give a uniform limp quality thereto.

Before the squeeze roller 33 can engage 30 the sheet of paper, the blanket 17 must move from engagement with the paper and the cylinder 11, said blanket passing from said engagement, about the guide rollers 19, 20 and 21. Hence the blanket upon its return 35 movement will have its inoperative reach pass through the liquid in the tank 10, any liquid expressed therefrom during its operative engagement with the cylinder 11 being thus restored thereto by absorption of the 40 liquid in the tank. The movement of the blanket 17 results in part from its pressure engagement with the cylinder 11, and in part from the positive rotation of the guide roller 18.

45 There being three sets of grippers upon the cylinder 11 in the form of the invention shown in the drawings, three sheets will be fed to the cylinder 11 during each rotation thereof, and since the R. P. M. of this cylinder will range from eleven to fifteen or 50 more per minute with the better grades of paper, it is apparent that the capacity of the machine is high, running from thirty to forty-five sheets per minute, or from approximately two thousand to twenty-seven hundred per hour.

It is apparent that each sheet of paper will be subjected to substantially identical conditions while passing through the machine, so 55 that there will be little variation in the condition of different sheets during a long run of the machine. The gradual lowering of the level of the liquid in the tank will have no appreciable modifying effect in the action 60 of the machine, since irrespective of this

level, the return or inoperative reach of the blanket 17 will be practically continuously immersed in the liquid from the time it leaves the roller 19 until it approaches the roller 18. If there is any variation in the 70 degree of saturation in different portions of this blanket, the roller 18 will tend to correct this condition, although the compression of the blanket in developing the requisite pressure against the blanket 12 will not be 75 sufficient to remove any substantial quantity of the liquid from the blanket as it is passing about said roller 18.

All of the dampening or wetting liquid 80 which is applied to the paper is expressed from an absorbent blanket, or blankets, thoroughly saturated with this liquid, thus ensuring uniformity in the distribution of the liquid throughout the paper. The application of a continuing pressure to the sheets 85 while between the blankets 12 and 17 ensures rapid absorption by the paper of the liquid expressed from a blanket while the entire sheet is thus subjected to pressure, not only giving increased capacity to the machine, but ensuring a rapid aging of the 90 paper.

The squeeze roller 33 is used because as the sheet passes from between the blankets 95 12 and 17, there is likelihood of the surface of the paper being fairly wet, since the time interval is not sufficient to complete the absorption of all of the moisture applied to the paper. The action of said roller will be such as to either force this moisture within 100 the paper, or remove it therefrom. The roller also acts to remove any excess moisture from the paper beyond that which may be required to properly condition it.

Adjustment of the squeeze roller with relation to the cylinder 11 may be resorted to, to vary the pressure exerted upon the sheet by this roller, and thus more or less control the quantity of liquid retained in the sheet. Ordinarily, however, with a machine operating at fairly high speeds, the difficulty encountered is not the removal of surplus liquid absorbed by the sheet, but the problem of causing a sheet to absorb sufficient of this liquid to properly condition it.

110 The adjustment of the roller 19 is utilized for taking up slack due to stretch of the blanket 17.

In a machine embodying my invention, the time interval for properly conditioning 120 each sheet, even of higher grade papers, will be but four or five seconds from the time the sheet leaves the shelf 14 until it is delivered to the shelf 41, and every sheet will be in practically the same condition as every other sheet. The short time interval, and the absence of any rubbing of the paper, permits the wetting or dampening of each sheet under conditions which will ensure substantially uniform expansion of the paper of 125 130

every sheet, and will avoid any injury to the surface finish thereof to a degree which would require refinishing of the paper after the impressions have been made and the sheet has been dried.

I have referred herein to a wetting or dampening liquid in the tank 10, this term being used because, with a long continued run of the machine, if water alone were used 10 in the tank, it would become polluted with some of the sizing used upon the paper, and might become foul through the fermentation of this material. Ordinarily this liquid will consist of water containing in solution there- 15 with, ingredients which will neutralize the substances which may enter the water from the paper sizing, these ingredients, however, having no tendency to injure the surface finish of the paper. The character of this 20 liquid, however, is immaterial to the invention, and water alone may be used if care is taken to prevent its becoming so foul as to impart an objectionable odor to the paper.

It is not my intention to limit the invention 25 to the precise details of construction shown in the drawings, it being apparent that such may be varied without departing from the spirit and scope of the invention.

Having described the invention, what I 30 claim as new and desire to have protected by Letters Patent, is:—

1. A paper wetting machine embodying therein a tank for the wetting liquid, a cylinder rotatably mounted within said tank, a 35 yieldable blanket carried by said cylinder, an endless absorbent blanket adapted to co-operate with the blanket upon said cylinder during a portion of each revolution of said cylinder, and guides for the operative reach 40 of said endless blanket in pressure relation to said cylinder and for the inoperative reach of said endless blanket positioned below the level of the wetting liquid within said tank and away from said cylinder whereby the 45 operative reach thereof is pressed tightly against the blanket upon said cylinder, and the inoperative reach thereof is passed through the liquid in said tank, so that a sheet delivered between said blankets will 50 be subjected to continuing pressure for a part of a revolution of said cylinder, and the moisture expressed from a blanket as a result of the pressure exerted by one of them upon the other, will be restored before the 55 same portion of the blanket is brought into engaging relation with another sheet.

2. A paper wetting machine embodying therein a tank for the wetting liquid, a cylinder rotatably mounted within said tank, a 60 yieldable blanket carried by said cylinder, an endless absorbent blanket adapted to co-operate with the blanket upon said cylinder during a portion of each revolution of said cylinder, guides for the operative reach of 65 said endless blanket in pressure relation to

said cylinder and for the inoperative reach of said endless blanket positioned below the level of the wetting liquid within said tank and away from said cylinder whereby the operative reach thereof is pressed tightly 70 against the blanket upon said cylinder, and the inoperative reach thereof is passed through the liquid in said tank, so that a sheet delivered between said blankets will be subjected to continuing pressure for a part 75 of a revolution of said cylinder, and the moisture expressed from a blanket as a result of the pressure exerted by one of them upon the other, will be restored before the same portion of the blanket is brought into 80 engaging relation with another sheet, and a squeeze roller in pressure engaging relation with the blanket upon said cylinder, and with a sheet of paper thereon after it has passed from between the blanket upon said 85 cylinder and said endless blanket.

3. A paper wetting machine embodying therein a tank for the wetting liquid, a cylinder rotatably mounted within said tank, a 90 yieldable blanket carried by said cylinder, an endless absorbent blanket adapted to co-operate with the blanket upon said cylinder during a portion of each revolution of said cylinder, a guide roller whereby said endless blanket is brought into engaging relation with the blanket upon said cylinder, said guide roller pressing said endless blanket toward said cylinder, a guide roller adapted to direct said endless blanket away from said cylinder after it has passed about a portion thereof, intermediate guide rollers positioned below the liquid level in the former of said tank, said guide rollers being so spaced as to press one reach of said endless blanket tightly against said last named blanket so that a sheet delivered between said blankets will be subjected to continuous pressure for a part of a revolution of said cylinder, and said intermediate guide rollers will cause 100 said blanket to be relieved from pressure, whereby moisture expressed from a blanket as a result of the pressure exerted by one of them upon the other will be restored before the same portion of the blanket is brought into 105 engaging relation with another sheet of paper, and means positively driving said first named roller, whereby each sheet of paper is subjected to excess moisture and an initial pressure, as it passes between said 110 blankets.

4. A paper wetting machine embodying therein a tank for the wetting liquid, a cylinder rotatably mounted within said tank, a 115 yieldable blanket carried by said cylinder, an endless absorbent blanket adapted to co-operate with the blanket upon said cylinder during a portion of each revolution of said cylinder, a guide roller whereby said endless blanket is brought into engaging relation with the blanket upon said cylinder, 120

- said guide roller pressing said endless blanket toward said cylinder, a guide roller adapted to direct said endless blanket away from said cylinder after it has passed about 5 a portion thereof, intermediate guide rollers positioned below the liquid level in the former of said tank, said guide rollers being so spaced as to press one reach of said endless blanket tightly against said last named 10 blanket so that a sheet delivered between said blankets will be subjected to continuous pressure for a part of a revolution of said cylinder, and said intermediate guide rollers will cause said blanket to be relieved from 15 pressure, whereby moisture expressed from a blanket as a result of the pressure exerted by one of them upon the other will be restored before the same portion of the blanket is brought into engaging relation with 20 another sheet of paper, means positively driving said first named roller, whereby each sheet of paper is subjected to excess moisture and an initial pressure, as it passes between said blankets, and a squeeze roller in press- 25 sure engaging relation with the blanket upon said cylinder, and with a sheet of paper thereon after it has passed from between the blanket upon said cylinder and said endless blanket.
- 30 5. A paper wetting machine embodying therein a tank for the wetting liquid, a cylinder rotatably mounted within said tank, a yieldable blanket carried by said cylinder, an endless absorbent blanket adapted to co- 35 operate with the blanket upon said cylinder during a portion of each revolution of said cylinder, guides for the operative reach of said endless blanket in pressure relation to said cylinder and for the inoperative reach 40 of said endless blanket positioned below the level of the wetting liquid within said tank and away from said cylinder whereby the operative reach thereof is pressed tightly against the blanket upon said cylinder, and 45 the inoperative reach thereof is passed through the liquid in said tank, so that a sheet delivered between said blankets will be subjected to continuing pressure for a part of a revolution of said cylinder, and the 50 moisture expressed from a blanket as a result of the pressure exerted by one of them upon the other, will be restored before the same portion of the blanket is brought into engaging relation with another sheet, a 55 squeeze roller, and adjustable bearing blocks for said squeeze roller whereby it may be brought into a desired pressure engaging relation with the blanket upon said cylinder, and with a sheet of paper thereon after it 60 has passed from between the blanket upon said cylinder and said endless blanket.
- 65 6. A paper wetting machine embodying therein a tank for the wetting liquid, a cylinder rotatably mounted within said tank, a yieldable blanket carried by said cylin- 70 der, an endless absorbent blanket adapted to co-operate with the blanket upon said cylinder during a portion of each revolution of said cylinder, a guide roller whereby said endless blanket is brought into engaging relation with the blanket upon said cylinder, adjustable bearings for said roller whereby it may be caused to exert a desired pressure through said endless blanket toward said cylinder, a guide roller adapted to direct 75 said endless blanket away from said cylinder after it has passed about a portion thereof, intermediate guide rollers positioned below the liquid level in the former of said tank, said guide rollers being so spaced as to press one reach of said endless blanket tightly against said last named blanket so that a sheet delivered between said blankets will be subjected to continuous pressure for 80 a part of a revolution of said cylinder, and said intermediate guide rollers will cause said blanket to be relieved from pressure, whereby moisture expressed from a blanket as a result of the pressure exerted by one of them upon the other will be restored before the same portion of the blanket is brought into engaging relation with another sheet of paper, and means positively driving said first named roller, whereby each sheet of paper is subjected to excess moisture and an initial pressure, as it passes between said blankets.
7. A paper wetting machine embodying therein a tank for the wetting liquid, a cylinder rotatably mounted within said tank, a yieldable blanket carried by said cylinder, an endless absorbent blanket adapted to co-operate with the blanket upon said cylinder during a portion of each revolution of said cylinder, a guide roller whereby said endless blanket is brought into engaging relation with the blanket upon said cylinder, said guide roller pressing said endless blanket toward said cylinder, a guide roller adapted to direct said endless blanket away 100 from said cylinder after it has passed about a portion thereof, adjustable bearings for said last named guide roller whereby said roller may be set to take up slack in said endless blanket, and regulate the pressure 105 exerted thereby toward said cylinder blanket, intermediate guide rollers positioned below the liquid level in said tank, said first named guide rollers being so spaced as to press one reach of said endless blanket tightly against said last named blanket so that a sheet delivered between said blankets will 110 be subjected to continuous pressure for a part of a revolution of said cylinder, and said intermediate guide rollers will cause said blanket to be relieved from pressure, whereby moisture expressed from a blanket 115 as a result of the pressure exerted by one of them upon the other will be restored before the same portion of the blanket is 120

brought into engaging relation with another sheet of paper, and means positively driving said first named roller, whereby each sheet of paper is subjected to excess moisture and an initial pressure, as it passes between said blankets.

8. A paper wetting machine embodying therein a tank for the wetting liquid, a cylinder rotatably mounted within said tank, 10 a yieldable blanket carried by said cylinder, an endless absorbent blanket adapted to co-operate with the blanket upon said cylinder during a portion of each revolution of said cylinder, a guide roller whereby said endless blanket is brought into engaging relation with the blanket upon said cylinder, adjustable bearings for said roller whereby it may be caused to exert a desired pressure through said endless blanket toward said cylinder, a 15 guide roller adapted to direct said endless blanket away from said cylinder after it has passed about a portion thereof, adjustable bearings for said last named guide roller whereby said roller may be set to take 20 up slack in said endless blanket, and regulate the pressure exerted thereby toward said cylinder blanket, intermediate guide rollers positioned below the liquid level in said tank, said first named guide rollers being so spaced 25 as to press one reach of said endless blanket tightly against said last named blanket so that a sheet delivered between said blankets will be subjected to continuous pressure for a part of a revolution of said cylinder, and 30 said intermediate guide rollers will cause said blanket to be relieved from pressure, whereby moisture expressed from a blanket as a result of the pressure exerted by one of them upon the other will be restored before 35 the same portion of the blanket is brought 40 into engaging relation with another sheet of paper, and means positively driving said first named roller, whereby said sheet of paper is subjected to excess moisture and an initial pressure, as it passes between said blankets.

9. A paper wetting machine embodying therein a tank for the wetting liquid, a cylinder rotatably mounted within said tank, 50 a yieldable blanket carried by said cylinder, an endless absorbent blanket adapted to co-operate with the blanket upon said cylinder during a portion of each revolution of said cylinder, a guide roller whereby said endless blanket is brought into engaging relation with the blanket upon said cylinder, adjustable bearings for said roller whereby it may be caused to exert a desired pressure through said endless blanket toward said cylinder, a 55 guide roller adapted to direct said endless blanket away from said cylinder after it has passed about a portion thereof, adjustable bearings for said last named guide roller whereby said roller may be set to take 60 up slack in said endless blanket, and regu-

late the pressure exerted thereby toward said cylinder blanket, intermediate guide rollers positioned below the liquid level in said tank, said first named guide rollers being so spaced as to press one reach of said endless 70 blanket tightly against said last named blanket so that a sheet delivered between said blankets will be subjected to continuous pressure for a part of a revolution of said cylinder, and said intermediate guide rollers will cause said blanket to be relieved from pressure, whereby moisture expressed from a blanket as a result of the pressure exerted by one of them upon the other will be restored before the same portion of the blanket is brought into engaging relation with another sheet of paper, means positively driving said first named roller, whereby said sheet of paper is subjected to excess moisture and an initial pressure, as it passes between said blankets, a squeeze roller, and adjustable bearing blocks for said squeeze roller whereby it may be brought into a desired pressure relation with the blanket upon said cylinder, and with a sheet of paper thereon after it has passed from between the blanket upon said cylinder and said endless blanket.

10. A paper wetting machine embodying therein a tank for the wetting liquid, a cylinder rotatably mounted within said tank, a yieldable blanket carried by said cylinder, different portions of said blanket being spaced apart, gripper mechanisms carried by said cylinder in said spaces, an endless absorbent blanket adapted to co-operate with the blanket upon said cylinder during a portion of each revolution of said cylinder, guides for the operative reach of said endless blanket in pressure relation to said cylinder and for the inoperative reach of said endless blanket positioned below the level of the wetting liquid within said tank and out of engaging relation with said cylinder whereby the operative reach thereof is pressed tightly against the blanket upon said cylinder, and the inoperative reach thereof is passed through the liquid in said tank, so that a sheet delivered between said blankets will be subjected to continuing pressure for a part of a revolution of said cylinder, and the moisture expressed from a blanket as a result of the pressure exerted by one of them upon the other, will be restored before the same portion of the blanket is brought into engaging relation with another sheet, a feed shelf, a feeding mechanism adapted to receive sheets from said shelf and deliver them to the grippers upon said cylinder, a collecting shelf spaced away from said cylinder, and a delivery mechanism adapted to receive sheets from said cylinder and pile them upon said collecting shelf, whereby said sheets, before being so piled, will be exposed for a short interval to the air.

11. A paper wetting machine embodying

therein a tank for the wetting liquid, a cylinder rotatably mounted within said tank, a yieldable blanket carried by said cylinder, different portions of said blanket being spaced apart, gripper mechanisms carried by said cylinder in said spaces, an endless absorbent blanket adapted to co-operate with the blanket upon said cylinder during a portion of each revolution of said cylinder, guides for the operative reach of said endless blanket in pressure relation to said cylinder and for the inoperative reach of said endless blanket positioned below the level of the wetting liquid within said tank and out of engaging relation with said cylinder whereby the operative reach thereof is pressed tightly against the blanket upon said cylinder, and the inoperative reach thereof is passed through the liquid in said tank, so that a sheet delivered between said blankets will be subjected to continuing pressure for a part of a revolution of said cylinder, and the moisture expressed from a blanket as a result of the pressure exerted by one of them upon the other, will be restored before the same portion of the blanket is brought into engaging relation with another sheet, a feed shelf, a feeding mechanism adapted to receive sheets from said shelf and deliver them to the grippers upon said cylinder, a collecting shelf spaced away from said cylinder, a delivery mechanism adapted to receive sheets from said cylinder and pile them upon said collecting shelf, whereby said sheets, before being so piled, will be exposed for a short interval to the air, a squeeze roller in pressure engaging relation with the blanket upon said cylinder, and with a sheet of paper thereon, and means rotating said squeeze roller, said squeeze roller being positioned between the point of disengagement of said endless blanket with the blanket upon said cylinder and said delivery mechanism.

12. A paper wetting machine embodying therein a tank for the wetting liquid, a cylinder rotatably mounted within said tank, a yieldable blanket carried by said cylinder, different portions of said blanket being spaced apart, gripper mechanisms carried by said cylinder in the spaced portions of said blanket, a feed shelf, a feeding mechanism adapted to receive sheets from said shelf and deliver them to the grippers upon said cylinder, an endless absorbent blanket adapted to co-operate with the blanket upon said cylinder during a portion of each revolution of said cylinder, a guide roller whereby said endless blanket is brought into engaging relation with the blanket upon said cylinder adjacent said feeding mechanism, said guide roller pressing said endless blanket toward said cylinder, a guide roller adapted to direct said endless blanket away from said cylinder after it has passed about a portion thereof, intermediate guide rollers positioned below the liquid level in said tank, the former of said guide rollers being so spaced as to press one reach of said endless blanket tightly against said last named blanket so that a sheet delivered between said blankets will be subjected to continuous pressure for a part of a revolution of said cylinder, and said intermediate guide rollers being positioned out of engaging relation with said cylinder, whereby moisture expressed from a blanket as a result of the pressure exerted by one of them upon the other will be restored before the same portion of the blanket is brought into engaging

below the liquid level in said tank and out of engaging relation with said cylinder, said guide rollers being so spaced as to press one reach of said endless blanket tightly against said last named blanket so that a sheet delivered between said blankets will be subjected to continuous pressure for a part of a revolution of said cylinder, and moisture expressed from a blanket as a result of the pressure exerted by one of them upon the other will be restored before the same portion of the blanket is brought into engaging relation with another sheet of paper, means positively driving said first named roller, whereby each sheet of paper is subjected to excess moisture and an initial pressure, as it passes between said blankets, a collecting shelf spaced away from said cylinder, and a delivery mechanism adapted to receive sheets from said cylinder and pile them upon said collecting shelf, whereby said sheets, before being so piled, will be exposed for a short interval to the air.

13. A paper wetting machine embodying therein a tank for the wetting liquid, a cylinder rotatably mounted within said tank, a yieldable blanket carried by said cylinder, different portions of said blanket being spaced apart, gripper mechanisms carried by said cylinder in the spaced portions of said blanket, a feed shelf, a feeding mechanism adapted to receive sheets from said shelf and deliver them to the grippers upon said cylinder, an endless absorbent blanket adapted to co-operate with the blanket upon said cylinder during a portion of each revolution of said cylinder, a guide roller whereby said endless blanket is brought into engaging relation with the blanket upon said cylinder adjacent said feeding mechanism, adjustable bearings for said roller whereby it may be caused to exert a desired pressure through said endless blanket toward said cylinder, a guide roller adapted to direct said endless blanket away from said cylinder after it has passed about a portion thereof, intermediate guide rollers positioned below the liquid level in said tank, the former of said guide rollers being so spaced as to press one reach of said endless blanket tightly against said last named blanket so that a sheet delivered between said blankets will be subjected to continuous pressure for a part of a revolution of said cylinder, and said intermediate guide rollers being positioned out of engaging relation with said cylinder, whereby moisture expressed from a blanket as a result of the pressure exerted by one of them upon the other will be restored before the same portion of the blanket is brought into engaging

relation with another sheet of paper, means positively driving said first named roller, whereby said sheet of paper is subjected to excess moisture and an initial pressure, as it 5 passes between said blankets, a squeeze roller, adjustable bearing blocks for said squeeze roller whereby it may be brought into a desired pressure relation with the blanket upon said cylinder, and with a sheet of 10 paper thereon after it has passed from between the blanket upon said cylinder and said endless blanket, a collecting shelf spaced away from said cylinder, and a delivery mechanism adapted to receive sheets from 15 said cylinder and pile them upon said collecting shelf, whereby said sheets, before being so piled, will be exposed for a short interval to the air.

14. A paper wetting machine embodying 20 therein a tank for the wetting liquid, a cylinder rotatably mounted within said tank, a plurality of yieldable absorbent blankets superimposed one upon the other upon said cylinder, an endless absorbent blanket adapted 25 to co-operate with the blankets upon said cylinder during a portion of each revolution of said cylinder, and guides for the operative reach of said endless blanket and in pressure relation to said cylinder, and for the inoperative reach of said endless blanket and out of 30 engaging relation with said cylinder whereby the operative reach thereof is pressed tightly against the blankets upon said cylinder, and the inoperative reach thereof is passed 35 through the liquid in said tank, so that a sheet delivered between said blankets will be subjected to continuing pressure for a part of a revolution of said cylinder, and the moisture expressed from the blankets as 40 a result of the pressure exerted by one of them upon the other, will be restored before the same portions of the blankets are brought into engaging relation with another sheet.

15. A paper wetting machine embodying 45 therein a tank for the wetting liquid, a cylinder rotatably mounted within said tank, a driving gear carried by said cylinder, means continuously rotating said gear, a yieldable blanket carried by said cylinder, different 50 portions of said blanket being spaced apart,

gripper mechanisms carried by said cylinder in said spaces, a feed shelf, a feeding mechanism adapted to receive sheets from said shelf and deliver them to the grippers upon said cylinder, gears in mesh with said driving gear and actuating said feeding mechanism, an endless absorbent blanket adapted to co-operate with the blanket upon said cylinder during a portion of each revolution of said cylinder, a guide roller whereby said endless blanket is brought into engaging 55 relation with the blanket upon said cylinder adjacent said feeding mechanism, gears in mesh with said driving gear and operative upon said guide roller, a guide roller adapted 60 to direct said endless blanket away from said cylinder after it has passed about a portion thereof, intermediate guide rollers positioned below the liquid level in said tank out of 65 engaging relation with said cylinder, the former of said guide rollers being so spaced as to press one reach of said endless blanket tightly against said last named blanket so that a sheet delivered between said blankets 70 will be subjected to continuous pressure for 75 a part of a revolution of said cylinder, and moisture expressed from a blanket as a result of the pressure exerted by one of them upon the other will be restored before the same portion of the blanket is brought into 80 engaging relation with another sheet of paper, a collecting shelf spaced away from said cylinder, a delivery mechanism adapted 85 to receive sheets from said cylinder and pile them upon said collecting shelf, whereby said sheets, before being so piled, will be exposed for a short interval to the air, gears connecting 90 said driving gear and said delivery mechanism, a squeeze roller in pressure engaging relation with the blanket upon said cylinder and with a sheet of paper thereon, said roller being positioned between the point of disengagement of said endless blanket with the blanket upon said cylinder and said delivery mechanism, and gears meshing with 95 said driving gear and rotating said squeeze roller.

In witness whereof I have hereunto affixed my signature, this 8th day of April 1924.

PETER AITCHISON.
